John Blair Sutton, Pittsburgh, Pa.

Application February 20, 1942, Serial No. 431,737

23 Claims. (Cl. 153—60)

This invention relates to metal rolling apparatus of the cross roll type and is especially concerned with such apparatus in which the size of the roll pass is variable to permit operation on different sizes of stock. The application hereof forms a continuation-in-part of my application Serial No. 350,390, filed August 3, 1940.

Cross rolling units of three rolls are desirable in that they eliminate supporting guides. The omission of guides is advantageous because of difficulties involved in adjusting guides to the correct height, when they wear off, or when other size stock is passed through the machine, as it is desirable to maintain a practically constant level for the center line of the pass, and because guides, even when properly adjusted, tend to mark the stock.

Another desirable result of using cross rolling units of three rolls, is that they permit such grouping of the rolls around the stock as to avoid the application of diametrically opposed pressure to the stock. This is of particular advantage in rolling thin wall tubes.

The size adjustment of a pass of three cross rolls presents a problem in that the angular spacing of the rolls about the center line of the pass must be preserved, that is to say, the angular relation of normals that cross the axes of the respective rolls in a given plane perpendicular to the center line of the pass must remain constant as the spacing of the rolls from the center line varies. Such plane is common for all three rolls, if they are so placed that it contains the minimum diameters of three rolls. I have succeeded in organizing a three-roll straightening pass, which as herein illustrated consists of one driven concave roll and two concave idler rolls, in which adjustment may be made in satisfactory manner by an adjusting movement of the two idler rolls without moving the driven roll. Since the surface of the driven roll is fixed and limits the pass upon one side, the center line of the pass moves laterally as the size of the pass is changed; and I have, therefore, provided for preserving the angular relation of the normals, to which reference is above made, in shifting the idler rolls along the paths followed in their adjusting movement. While this adjustment avoids necessity for transverse movement of the primary, or driven roll, it is to be understood that transverse adjustment of that roll may be provided. Thus my companion application Serial No. 431,738, filed February 20, 1942, shows means providing for the transverse adjustment of the primary roll

along lines normal to the center on which the primary roll is pivoted for angular axial adjustment.

One object of my invention is to provide cross-roll straightening and finishing apparatus comprising one or more sets or groups composed of a primary, or driven roll and two secondary, or idler rolls, in which the two secondary, or idler, rolls are adjustable toward and from set positions of the primary roll in varying the dimensions of the stock-contacting pass in which the rolls contact the stock acted on in the apparatus.

Another object of my invention is to provide a system of roll mounting and arrangement in which the paths followed by two of the rolls in their adjusting movement are so related to each other, and to the set position of the primary roll that the normals crossing the axes of the two adjustable rolls at a common plane perpendicular to the center line of the pass remain related at unchanging angles as the positions of the idlers are changed.

Another object of the invention is to provide simple and effective structure for causing the two adjustable rolls of the three-roll pass assembly to be simultaneously and equally moved along their correlated paths, and for mounting and backing those rolls at any selected points along their paths.

In the accompanying drawings, Fig. I is a plan view of a straightening machine embodying the above-indicated invention; Fig. II is a diagrammatic vertical section through one of the roll passes with an adjustment to convenience in that the true circular diameters of the rolls, rather than their distorted shape at the plane of intersection, is shown; Fig. III is a vertical sectional detail view of one of the passes. Fig. IV is a detail front elevation of one of the idler roll brackets of the machine assembly shown in Fig. III. Fig. V is a view similar in arrangement to Fig. III but illustrating a modification in structure, to provide independent wear adjustment of the two idler rolls of the machine. Fig. VI is a front elevation of one idler roll bracket appropriate to either of the idler roll brackets of the modified assembly shown in Fig. V.

The invention is illustrated as embodied in a straightening machine comprising a first pass of concave cross rolls 1, 2 and 3, an intermediate deflecting roll 4, and a second pass of concave cross rolls 5, 6 and 7. In operation of the apparatus, stock designated by reference numeral 8, enters the first pass, progresses past roll 4,

which usually is adjusted to deflect the stock, and progresses through the second pass. The rolls 1 and 5 of the cross-roll passes are driven, the opposed paired rolls 2-3 and 6-7, although they may be driven, are shown as idlers. The roll units are mounted in a housing 9, and driven rolls 1 and 5 are positively impelled through reduction gearing by a motor 10, in the directions of rotation indicated by the arrows.

Referring to Fig. II of the drawings, which is taken diagrammatically on a plane perpendicular to the center line of the roll pass, the paths followed by the idler rolls in their adjusting movement, and the determinants for such paths are shown. The center line of the pass is designated C, and from the center line extend normals C-A, C-B and C-D, that respectively cross the axes F, G and J of the driven roll 1, and the idler rolls 2 and 3. The ideal angular grouping of the rolls about the pass is the one which permits the largest possible rolls for the smallest required stock. As the rolls 2 and 3 are shown of the same size, and smaller than roll 1, angles A-C-B and A-C-D will be equal and both larger than angle B-C-D, to conform to the ideal arrangement. To enlarge the pass to accommodate larger stock, indicated by the circle 11, by shifting the idler rolls 2 and 3 while retaining constant the angular relation with the normals, the rolls are moved along the paths G-H and J-K. These paths are related to the normals C-B and C-D at angles, designated b, that are in the illustrated structure equal to each other, and that are one-fourth as great as the angles that separate the normals.

The angular relation of these paths with the normals is determined in the following manner: The angles, designated a, between normal C-A extended, and normals C-B and C-D respectively, are both one-half as great as the angle separating the normals of the rolls 2 and 3. The radius of the stock 8 of minimum diameter may be termed r_8 , and that of the larger stock 11, adjustment for which is shown may be called r_{11} . The equal minimum radius of rolls 2 and 3 is for convenience called r_2 . The center line of the enlarged pass being designated E, distance E-H minus distance C-G must equal distance C-E, because the line E-H is equal to r_{11} (the radius of the larger stock) plus r_2 (the minimum radius of the idler roll 2), and the difference between r_{11} and r_8 is equal to C-E. The distance G-H is therefore the resultant of two components of equal size: C-E and (E-H minus C-G) forming with them a diagonal of inclination $b=a/2$ in a rhombus of an inclination angle a. Since angles a are one-half as great as angle BCD, angles b are one-quarter as great as angle BCD.

The above gives the derivation for the establishment of ideal paths of movement for adjustment of the idler rolls to stock of different sizes. Some deviation from the mathematical ideal is, however, permissible; and satisfactory results are obtained by a relatively close approximation to the mathematical ideal. This is particularly the case if some slight transverse adjustment of the primary, or driven rolls be provided, as by accommodating the roll mountings in slide blocks mounted for movement transversely of the apparatus frame, and propelled by suitable means such as adjusting screws.

In the illustrated embodiment of my invention the driven roll 1 (of one roll set) is mounted in a bracket 12 mounted for swinging motion on an

axis that coincides with the normal C-A. Idler roll 2 is mounted in a bracket 13 that is swivelled to swing upon an axis coincident with normal C-B, so that, in appropriate manner it may be adjusted for contact with stocks of different sizes. The adjustment may be accomplished by means of a handle 14 secured to a plate 15, which in turn is secured to the bracket 13. Locking screws 16 are mounted in the bracket 13, and extend through arcuate slots 17 in a slideable carriage 18 upon which the bracket is swivelled.

Idler roll 3 is mounted in a bracket 35 for swinging movement on an axis that coincides with the normal C-D, a handle 14' being provided for swinging the bracket. This handle 14' is carried by a plate 15', which in turn is secured to the bracket 35, locking screws 40 are mounted in the bracket 35, and extend through arcuate slots in a slideable carriage 41 upon which the bracket is swivelled.

By movement of these slideable carriages 18 and 41, the idler rolls 2 and 3 are simultaneously adjustable along lines closely approximating the lines C-H and C-K, respectively, to maintain a true pass line in their adjusted positions. To this end the carriage 18 for idler roll 2 and the carriage 41 for idler 3, are respectively slideable in a way between guides 19, and in a way between guides 19'. Both the guides 19 and the guides 19' are carried in a vertically-divided guide block 20, one-half of which is shown in Fig. III of the drawings. Adjacent both the guide 19 and the guide 19' there are shown surfaces 21, 22 and 23 which are provided for meeting with similar surfaces of the other portion of the guide block. The halves of the guide block 20 are relatively positioned by shoulders 25 and 26 (shown in Fig. III) and by matching shoulders on the other half of the guide block; and the halves of the guide block are held together by bolts 24 extended through both halves of the block.

For adjusting movement, guide block 20 is slideable as a whole on a mounting plate 27; movement of the guide block on the mounting plate being limited by a key and keyway connection 28 to a direction parallel to the axial centerline of the pass. Plate 27 itself is adjustable with respect to the machine frame 9, its adjustment being limited to a direction transverse to the pass line by a key and keyway connection 29. Overall adjustment transversely of the pass is effected by means of adjusting screws 30, which move the plate 27, carrying the guide block 20 in a direction limited by the keyed connection 29 to a transverse direction with respect to the axis of the pass. Nuts 31 fix this adjustment when made; and the assembly is held firmly together by set-screws 32, equipped with lock nuts 33. Adjusting screws 30 lie in slots 34 of the frame arranged to permit the above-described adjustment of the guide block parallel to the pass line. This transverse adjustment is in compensation for wear, and is one which is not frequently made.

The lines G-H and J-K, along which the roll carriages 18 and 41 move in sliding between guides 19 and 19' respectively, converge at a single point on the normal A-C, since the angular relation of the lower guides to the normal C-D corresponds to that of the upper guides to normal C-B, the two angles b indicated in Fig. III being equal. It will be noted that normal C-A bisects the angle BCD of the normals, and also the angle between the center lines of the paths defined by the two sets of guides 19.

As illustrated, the apparatus is organized with

respect to a minimum diameter of the stock, the primary roll of each three-roll group being mounted without provision for transverse adjustment, and accommodation to stock of larger sizes is made by retracting the two opposed secondary rolls along paths that converge to a point beyond the center line of the pass. If, however, the primary roll be made transversely adjustable in some manner as above indicated, that roll may be set in an advanced position, cooperatively with the paired secondary rolls to define the pass for minimum stock diameter. When both the paired secondary rolls and the primary rolls are then retracted to accommodate the pass through the group to stock of larger size, the lateral shifting of the pass will be such that the convergent paths along which the secondary rolls are moved will tend to meet at, rather than beyond, the center line of the pass. In such case it is desirable that the adjustment of the secondary rolls be made at least partially by the means provided for wear adjustment of the secondary rolls.

Adjustment of the carriages 18 and 41 in their respective guide ways is accomplished by means of a toggle link 43 arranged between, and connected with the shoes 18 and 41 by toggle arms 44. The link 43 is movable along a path midway between the converging guides and bisects the angle between them, such path being along the normal A—C extended. A key 45 extends from each side of the link 43 for engagement in ways in the block 20 for guiding the link in the correct path.

A screw 46, which is by means of a collar 46a and a nut 46b held against axial movement in the frame, extends through a threaded bore in the link for moving the latter as the screw is turned. The bearing block 20 has an extension 47 through which the screw 46 extends, and which is movable longitudinally of the frame to permit longitudinal motion of the block 20 and mechanism that it supports.

The adjusting screw 46 is provided with a screw-controlled locking device 59 by means of which the toggle link 43, and consequently the slide shoes or carriages 18 and 41 and rolls 2 and 3 may be secured in adjustment. A hand wheel 51 is provided for turning the screw to effect adjustments.

Locking engagement of bracket 35 is provided for by means of a bolt 36 which has a head bearing against a conical surface 33 having therein a slot 37 in which the shank of the bolt lies. Bolt 36 may be tightened by means of a nut 36a available at the front of the machine. The slide shoe or carriage 41 is constructed with a hole through which the bolt 36 passes, so that it may extend out through a slot 42 in the main frame of the machine to be engaged by the nut 36a.

In the machine illustrated, the central idler roll unit 52 has a single roll 4, mounted in a bracket that can swing around a horizontal axis that is perpendicular to the pass line. Adjustment of the roll 4 may be accomplished by means of a handwheel 53, in known manner.

It is to be understood that substantial change in both the mounting structure for the rolls and in the roll arrangement may be made. The illustrated embodiment of my invention is a cross-roll straightening apparatus in which two three-roll groups are spaced longitudinally of the apparatus frame, as entering and leaving groups or sets of cross-rolls, with a single pressure roll mounted between the two three-roll groups to bear intermediately on stock held in them. If

desired, however, a pair of rolls, such as the pair of idlers in the three-roll groups may be substituted for the single pressure roll, or a pair of opposed cross-rolls or even an additional three-roll group may be substituted, or the intermediate roll may be omitted. Also it is to be understood that one of the three-roll groups or sets may be used above as a straightening pass, particularly for small diameter stock which does not have any long-radius bends or sweeps; and that one of the three-roll groups may be used in association with any organization of opposed pairs of rolls.

The operation and advantages of a roll pass assembled and supported as described will be readily apparent. Adjustment of the size of the pass is accomplished by the simple operation of turning the handwheel 51, by means of which the link 43 is moved and consequently the carriages are moved simultaneously and equally along the correct paths to maintain the proper relation of the two adjustable rolls as they are moved toward and from the stationary roll.

Referring to the structure shown in Fig. III of the drawings, accommodation to wear of the driven roll 1, or to equal wear on the idler rolls 2 and 3 is provided. Thus, if there be, for example, a wear of $\frac{1}{2}$ inch on the driven roll 1, accommodation to the wear may be made by adjusting both of the idler rolls 2 and 3 toward roll 1 that same distance along the normal A—C. Likewise, if there be equal wear on the idler rolls 2 and 3, accommodation to such wear might be made by equally moving the idler rolls 2 and 3 an equal distance away from the roll 1 along the normal A—C extended. Movement in both directions along normal A—C may be had by adjustment of guide block 20.

The adjustment shown in Fig. III does not, however, provide accommodation to unequal wear of the rolls 2 and 3. It should be understood that if there were provision for adjustment of the rolls 2 and 3 along their normals C—B and C—D (not their paths C—H and C—K for adjustment of the pass diameter) all the above wear accommodations would be obtained, since the effect would be an accommodating adjustment along the normal A—C, or A—C extended, as a resultant. If such adjustment of the rolls 2 and 3 is made independent, accommodation to unequal wear of those rolls is additionally obtained. For example, a wear of $\frac{1}{2}$ inch on roll 2 alone can be compensated by independently adjusting that roll $\frac{1}{2}$ inch along normal A—C extended toward C, without moving roll 3. Similarly accommodation to wear on roll 3 alone may be made by moving it, without moving roll 2. If both rolls 2 and 3 be worn, but unequally worn, accommodation may be made by adjusting both rolls unequally along their normals C—B and C—D. If lateral adjustment of the primary roll is provided it is desirable, as above noted, to utilize the wear adjustment of the secondary rolls in making a pass adjustment.

The modification illustrated in Figs. V and VI provides for independent adjustment of rolls 2 and 3 in accommodation to wear. In those figures of the drawings accommodating adjustment is similarly provided in the bracket 13' of roll 2, and in the bracket 35' of roll 3. A description of bracket 13', and the adjusting means associated with it, will serve therefore to describe both brackets.

Referring therefore to the structure of bracket

13', wedges 54 and 55 between the bracket and its carriage ride upon cooperatively inclined surfaces 54a and 55a. Wedges 54 and 55 are clampingly held, and may be forced toward each other by a bolt 58, having a square head 58a bearing against the wedge 55 and a nut 59 bearing against the wedge 54. An extension bolt 56 on the roll trunnion, having a nut 57, opposes bracket movement under the influence of the wedges 54 and 55, bolt 58, and nut 59. To make an adjustment along the normal C—B toward the point C, nut 57 is retracted to allow for the adjustment, and nut 59 is tightened, moving the wedges inwardly, and forcing the bracket 13' toward the point C. Adjustment away from the point C is made by retracting nut 59, and tightening nut 57. As above noted, the means for adjusting bracket 35' are identical with the means described.

An oblong hole, or slot, 60 in each of the brackets permits adjusting movement of the bracket and guides the bolt 58, which in turn by extending through holes 61 guides the wedges 54 and 55 when the bracket is swung to adjust the angular position of the roll. Bolt 58 is held against turning by its square head 58a lying in a squared recess 55b in the wedge 55.

In the modification of Figs. V and VI certain elements of the structure shown in Figs. III and IV may be omitted. Because adjustment of guide block 20 is made unnecessary, the guide block may lie directly against the housing 9, and the plate 27 with its keyways (as shown in Fig. III) is omitted. Guide block 20 is secured in the assembly of Fig. V by studs 62 passed through nuts 63. Slots 34 (as in Fig. III) permit adjustment of guide block 20 and the rolls 2 and 3 along the pass line.

Rotation of the brackets 13' and 35' is normally prevented by the frictional contact between the brackets and their associated wedges, and for this reason the screws 16 and 48, and the bolt 36, of the assembly shown in Fig. III are unnecessary. To make swinging adjustment of a roll, the nut 59 on its bolt 58 is loosened, and is retightened after the angular adjustment has been made. The wedges 54 and 55 are shown perpendicular to the axis of the rolls, but the inclined surfaces 64 with which the inclined faces of the wedges cooperate may be placed in any angular relation to the axes of the rolls which may conveniently conform to space requirements and the operation of nut 59 in permitting adjustment or fixing the position of the brackets.

Whereas in the illustrated embodiment of my invention each roll pass is shown as a three-roll pass consisting of a single driven roll and two paired idler rolls, that specific organization is not essential to my invention, which resides in the organization of one or more three-roll groups, or sets, in a cross-roll straightening apparatus, and in providing adjustment to conform a three-roll pass to stock of different sizes, rather than in the driving of the rolls. Thus by the use of properly organized driving means and connections of known sort, all three rolls of the pass may be driven, or if desired the paired adjustable rolls may be driven and the single roll may be an idler roll.

I claim as my invention:

1. In cross-rolling apparatus including grouped rolls that form a pass, said rolls including a pair of adjacent rolls the axes of which are arranged at angles to each other and to the center line of the pass, and said paired rolls being angularly

so spaced from the center line of the pass that normals of the pass that cross the respective axes of the rolls upon a plane perpendicular to the center line thereof at the smallest diameters of the rolls are angularly related in accordance with a minimum stock diameter of the pass, means for varying the size of the pass while maintaining the proper relative positioning and angular relations of the rolls that comprises mechanism organized laterally to move the adjacent paired rolls toward and away from the pass, and structure arranged to constrain such motion of the respective rolls to angularly related paths that converge beyond the center line of the pass and that are arranged at approximately equal angles to normals of the pass that respectively cross the axes of the paired rolls at a common plane perpendicular to the center line of the pass, the approximately equal angles which the said paths form with the said normals being substantially one-quarter as great as the angle separating the normals.

2. In cross-rolling apparatus including a concave driven roll and a pair of concave idler rolls, said rolls being grouped to form a pass and having their axes arranged at angles to each other and to the center line of the pass, said rolls being so angularly spaced about the center line of the pass that normals of the pass that cross the respective axes of the rolls upon a plane perpendicular to the center line thereof at the smallest diameters of the rolls are angularly related in accordance with a minimum stock diameter of the pass, means for varying the size of the pass while maintaining the proper spacing and angular relation of the rolls, said means comprising mechanism organized laterally to move the idler rolls toward and away from the pass while maintaining their angular relation to each other and to the center line of the pass, and guide members arranged to constrain the lateral motion of the idler rolls to paths that bear an approximately equal angular relation to the normals of the pass that cross the axes of the rolls at their smallest diameters.

3. In cross-rolling apparatus including a frame, a roll having a laterally fixed mounting in the frame, a pair of laterally movable rolls, said three rolls being grouped to form a pass and having their axes arranged at angles to each other and to the center line of the pass, a roll-supporting assembly for said laterally movable rolls comprising carriages respectively supporting the said rolls in determined angular relation to each other and to the center line of the pass, guide members mounted on the frame and slideably supporting the carriages, said guide members being arranged to guide the said carriages respectively along paths that bear an approximately equal angular relation to normals that cross the axes of the said laterally movable rolls at a plane perpendicular to the center line of the pass and that converge toward a point beyond the center line of the pass, and operating mechanism organized simultaneously and equally to move the carriages along the guide members to vary the size of the pass.

4. In cross-rolling apparatus including a frame, a laterally fixed roll supported by the frame, a pair of laterally movable rolls, said three rolls being grouped to form a pass and their axes being arranged at angles to each other and to the center line of the pass, and a supporting assembly for the said laterally movable rolls in accordance with claim 3, wherein the carriages are provided

with swivel-mounted roll supports by means of which the angular position of the rolls may be adjusted.

5. In cross-rolling apparatus including a frame, a roll having a laterally fixed mounting in the frame, a pair of laterally movable rolls, said rolls being grouped to form a pass and their axes being arranged at angles to each other and to the center line of the pass, and a supporting assembly for the said laterally movable rolls in accordance with claim 3, wherein the carriages are provided with swivel-mounted roll supports by means of which the angular position of the rolls may be adjusted, and wedging assemblies in said roll supports organized to vary the mounted distance of the said rolls from the pass in accommodation to wear on the rolls.

6. In cross-rolling apparatus that includes a frame, a concave laterally fixed roll mounted on the frame and a pair of concave laterally movable rolls, said rolls being grouped to form a pass and having their axes arranged at angles to each other and to the center line of the pass, and said rolls being so angularly spaced about the center line of the pass that normals of the pass that cross their axes at a plane perpendicular to the center line of the pass at the smallest diameters of the rolls are related in accordance with the minimum stock diameter of the pass, adjustable supporting assemblies for the respective laterally movable rolls comprising carriage that are movable along the paths that converge toward the opposite side of the center line of the pass and that lie between and bear approximately equal angular relation to the said respective normals, and roll supports that respectively carry the laterally movable rolls and that are swiveled to the respective carriage upon centers that coincide with said normals crossing the axes of the said rolls.

7. In cross-rolling apparatus that includes a frame, a concave laterally fixed roll mounted on the frame and a pair of concave laterally movable rolls, said rolls being grouped to form a pass and having their axes arranged at angles to each other and to the center line of the pass, and said rolls being so angularly spaced about the center line of the pass that normals of the pass that cross their axes at a plane perpendicular to the center line of the pass at the smallest diameters of the rolls are related in accordance with the minimum stock diameter of the pass, adjustable supporting assemblies for the respective laterally movable rolls comprising carriages that are movable along paths that converge toward the opposite side of the center line of the pass and that lie between and bear approximately equal angular relation to the respective said normals, roll supports that respectively carry the laterally movable rolls and that are swiveled to the respective carriages upon centers that coincide with said normals crossing the axes of the said rolls, and adjusting means in the said roll supports organized to vary the mounted position of the said rolls along the said normals in accommodation to wear on the rolls.

8. Cross-rolling apparatus comprising a frame having a member extending longitudinally parallel to the direction of motion of the stock to be rolled, a supporting block movably mounted upon said member for longitudinal and transverse adjustment therein, a pair of angularly related, converging guides carried by the block, roll-supporting carriages adjustable along said converging guides and respectively supporting each one roll of a pair of rolls, a laterally fixed roll mounted

on the frame in a position to cooperate with the laterally movable rolls to form a pass, the rolls being so spaced about the center line of the pass that normals crossing the axes of the laterally movable rolls are related at an angle greater than that between the converging guides, and the said normal that crosses the axis of the laterally fixed roll approximately bisects the angle between the said guide members.

10. Cross-rolling apparatus in accordance with claim 8 wherein the supporting block is movably mounted upon a carrying element for adjustment in directions longitudinal of the frame member, and the carrying element is movably mounted on the frame member for adjustment in directions transverse to said member.

15. Cross-rolling apparatus in accordance with claim 8 wherein the supporting block is divided in a plane perpendicular to the center line of the pass into portions having meeting faces, said meeting faces being provided with ways that cooperate to form the converging guides.

20. Cross-rolling apparatus in accordance with claim 8 wherein the supporting block is vertically divided in a plane perpendicular to the center line of the pass into portions having meeting faces, said meeting faces being provided with ways that cooperate to form the converging guides, and said portions between the ways being pocketed to provide a space between them, and operating mechanism for moving the carriages is mounted in the space provided by the pockets in said elements.

25. Cross-rolling apparatus including a concave laterally fixed roll and a pair of concave laterally movable rolls, said rolls being grouped to form a pass and having their axes arranged at angles to each other and to the center line of the pass, said rolls being so angularly spaced about the center line of the pass that normals of the pass that cross the respective axes of the rolls upon a plane perpendicular to the center line thereof at the smallest diameters of the rolls are angularly related in accordance with the minimum stock diameter of the pass, means for varying the size of the pass while maintaining the proper spacing and angular relation of the rolls, said means comprising mechanism for laterally moving the said laterally movable rolls toward and away from the pass while maintaining their angular relation to each other and to the center line of the pass, and guide members for constraining the lateral motion of the said laterally movable rolls to paths that are angularly related to the normals of the pass that cross the axes of the rolls at their smallest diameters.

30. Cross-rolling apparatus including a concave laterally fixed roll and a pair of concave laterally movable rolls, said rolls being grouped to form a pass and having their axes arranged at angles to each other and to the center line of the pass, said rolls being so angularly spaced about the center line of the pass that normals of the pass that cross the respective axes of the rolls upon a plane perpendicular to the center line thereof at the smallest diameter of the rolls are angularly related in accordance with the minimum stock diameter of the pass, means for varying the size of the pass according to claim 12, wherein the guide members are arranged to constrain the lateral movement of the said laterally movable rolls to straight paths that converge beyond the center line of the pass and that are related to the normals of the pass that cross the axes of the said laterally movable rolls

at their smallest diameters at angles substantially one-quarter as great as the angles between said normals.

14. In cross-rolling apparatus including grouped rolls that form a pass, said rolls including a pair of adjacent rolls the axes of which are arranged at angles to each other and to the center line of the pass, and said paired rolls being angularly spaced from the center line of the pass, means for varying the size of the pass while maintaining the proper relative positioning and angular relations of the rolls that comprises mechanism organized laterally to move the adjacent paired rolls toward and away from the pass, structure arranged to constrain such motion of the respective rolls to angularly related paths that converge toward the pass and that bear an approximately equal relation to normals of the pass that respectively cross the axes of the paired rolls at a common plane perpendicular to the center line of the pass, and roll supports for the said paired rolls organized to adjust the said rolls individually toward and from the pass along the said normals in accommodation to wear on the rolls.

15. In cross-rolling apparatus including grouped rolls that form a pass, said rolls including a pair of adjacent rolls the axes of which are arranged at angles to each other and to the center line of the pass, and said paired rolls being angularly spaced from the center line of the pass, means for varying the size of the pass while maintaining the proper relative positioning and angular relations of the rolls that comprises mechanism organized laterally to move the adjacent paired rolls toward and away from the pass, structure arranged to constrain such motion of the respective rolls to angularly related paths that converge beyond the center line of the pass and that are arranged at approximately equal angles to normals of the pass that respectively cross the axes of the paired rolls at a common plane perpendicular to the center line of the pass, the approximately equal angles which the said paths form with the said normals being substantially one-quarter as great as the angle separating the normals, and roll supports for the said paired rolls organized to adjust the rolls individually toward and from the pass along the said normals in accommodation to wear on the rolls.

16. In cross-rolling apparatus a three-roll pass composed of concave cross rolls, one roll of the pass being mounted in opposition to the other two thereof and immovable toward or from the center line of the pass, and the other two rolls of the pass being movable toward and from a point beyond the center line of the pass along converging paths.

17. In cross-rolling apparatus a three-roll pass

composed of concave cross rolls, one roll of the pass being mounted in opposition to the other two thereof and immovable toward or from the center line of the pass, and the other two rolls of the pass being movable toward and from a point beyond the center line of the pass along converging paths, which intersect beyond the center line of the pass.

18. Cross-rolling apparatus including at least two sets of three cooperative concave cross rolls grouped together to form of each group a straightening pass, two of said rolls in each pass being adjustable as a unit toward and from a fixed position of the third said roll mounted in opposition thereto, one said pass being at the entering end of the apparatus and the other being at the leaving end of the apparatus, and means for directly driving at least one roll in each three-roll pass.

19. Cross-rolling apparatus including at least two sets of three cooperative concave cross rolls grouped together to form of each group a straightening pass, two of said rolls in each pass being adjustable as a unit toward and from a fixed position of the third said roll mounted in opposition thereto, one said pass being at the entering end of the apparatus and the other being at the leaving end of the apparatus, means for directly driving at least one roll in each three-roll pass, and at least one deflecting roll placed between the two said three-roll passes.

20. Cross-rolling apparatus in accordance with claim 18, in which two rolls of each three-roll pass are movable toward and from a fixed position of the third said roll of the pass along converging paths.

21. Cross-rolling apparatus in accordance with claim 19, in which two rolls of each three-roll pass are movable toward and from the center line of the pass along converging paths.

22. In cross-rolling apparatus a group of three rolls mounted with relatively inclined axes to form a straightening pass, one roll of the said three-roll group being a concave roll longer than either of the two other rolls and mounted in opposition to them, and the said two other rolls being movable toward and from the said longer roll along convergent paths.

23. In cross-rolling apparatus a group of three rolls mounted with relatively inclined axes to form a straightening pass, one roll of the said three-roll group being a concave roll longer than either of the two other rolls and mounted in opposition to them, and the two other rolls being movable toward and from the said longer roll along convergent paths which intersect beyond the center line of the pass formed by the said three-roll group.

JOHN BLAIR SUTTON.
